(57) **CLAIM**

The ornamental design for a miniature football helmet liquid bottle pourer, as shown and described.

DESCRIPTION

FIG. 1 is a right side elevational view of a miniature football helmet liquid bottle pourer showing our new design;

FIG. 2 is an enlarged front view thereof;

FIG. 3 is a slightly reduced left side view thereof;

FIG. 4 is a greatly enlarged top plan view thereof;

FIG. 5 is a rear view of FIG. 3;

FIG. 6 is a bottom plan view as enlarged as FIG. 4;

FIG. 7 is an exploded perspective view thereof; and,

FIG. 8 is an exploded right side view thereof.
